DESIGN FOR A CIGAR-LIGHTER.

Design No. 13,810, dated March 27, 1883.

Fig: 2

UNITED STATES PATENT OFFICE.

GUSTAV FUCHS, OF CHICAGO, ILLINOIS.

DESIGN FOR A CIGAR-LIGHTER.

SPECIFICATION forming part of Design No. 13,810, dated March 27, 1883.

Application filed February 21, 1883. Term of patent 3½ years.

To all whom it may concern:

Be it known that I, GUSTAV FUCHS, of Chicago, in the county of Cook and State of Illinois, have invented a new and original Design 5 for Cigar-Lighters, of which the following is a specification.

Figure 1 is a perspective view of my new cigar-lighter; Fig. 2, a top view of the same.

This invention relates to the new configuration or shape of a cigar-lighter; and it consists in making the main portion thereof in form of a house placed on a platform, which also carries the ornamental cigar-cutter, and is provided with chimney-like projections for holding the splints and the sand for extinguishing the same, all as hereinafter more fully described.

In the accompanying drawings, the letter A represents an angular base or platform, 20 upon which stands the house-like body B of my new cigar-lighter, said body B having on its top chimney-shaped splint and sand holders C and D. One of the projections, D, is hid-

den behind the gable of the roof in Fig. 1, but is plainly shown in Fig. 2. Through an 25 aperture, a, in the gable of the roof can be seen the lamp E, the chimney of which extends through the top of the structure B. On the platform A, near one corner of the same, stands the ornamental cigar-cutter F.

I claim—

1. The design for a cigar-lighter, the same consisting of the platform A, house-like body B, chimney-shaped splint and sand holders C D, and lamp E, substantially as shown.

2. The design for a cigar-lighter, the same consisting of the platform A, having house-like body B and ornamental cutter F, the body B carrying the projections C D and lamp E, substantially as shown.

This specification of my invention signed by me this 22d day of January, 1883.

GUSTAV FUCHS.
